UNITED STATES PATENT OFFICE.

EUGENE TERRY, OF ITHACA, NEW YORK.

ADJUSTABLE FOOT-REST FOR RADIATORS, &c.

SPECIFICATION forming part of Letters Patent No. 784,711, dated March 14, 1905.

Application filed May 8, 1903. Serial No. 156,153.

To all whom it may concern:

Be it known that I, EUGENE TERRY, residing at Ithaca, in the county of Tompkins and State of New York, have invented certain new and useful Improvements in Adjustable Foot-Rests for Radiators, &c., of which the following is a full, clear, and exact description, such as will enable others skilled in the art to which it appertains to make and use the same.

10 This invention relates to an adjustable foot-rest for a radiator; and its object is to provide a foot-rest or shelf for use in connection with radiators or similar articles which may be readily secured to the radiator, removed therefrom, and adjusted to various positions thereon.

An embodiment of the invention is illustrated in the accompanying drawings, in which—

20 Figure 1 is a face view of the radiator, showing the foot-rest in position thereon. Fig. 2 is an end view with parts broken away. Figs. 3 and 4 are sectional views showing two different positions of the foot-rest. Figs. 5 to 25 9, inclusive, are details of various parts.

Similar reference characters refer to similar parts throughout the several views.

The invention is herein shown in connection with a radiator A of usual construction. The 30 foot-rest is shown as a shelf 1, pivotally mounted upon arms 2, projecting inwardly from rods 3, which are adapted to pass between adjacent sections of the radiator and which are provided at one end thereof with heads 4, preferably loosely slipped thereover, as shown, and adapted to serve as abutments against which pressure may be exerted when nuts 5 at the opposite ends of the rods are turned up to hold the rods in any desired position vertically of the radiator. There are preferably 40 two of these adjustable pivot-rods—one at each end of the shelf—and the parts 4 and 5 are also preferably provided with faces adapted to fit between the radiator to hold the parts firmly in place without slipping. Below the 45 plane of the shelf a rod 6 passes between the two adjacent radiator-sections, preferably at about the middle of the shelf, as shown, one end of said rod carrying an adjusting-nut 7 and the other a plate 8, provided with an ap-

erture through which passes a notched arm 9, having an upwardly-projecting lug or handle 9^a and pivoted between lugs 10, depending from the shelf. The plate 8 is preferably beveled, as at the point 11, to facilitate the engagement therewith of the notched teeth of the arm 9. 55

It will be seen that the foot-rest and its support constructed as described may be removed bodily from the radiator without in any way 60 affecting the appearance thereof, that it may be adjusted to any desired height by moving the supporting-rods 3 and 6 up or down between sections after having loosened their clamping-nuts, and that the foot-rest itself in 65 addition to this vertical adjustment may be given a swinging or angular adjustment by raising the arm 9 slightly and moving it to engage different teeth with the beveled edge 11 of the detent-plate.

The fact, which is especially applicable to simple constructions of this character, should be obvious that various changes in detail and in construction of parts may be made, that elements may be substituted, or other changes 7 made in the construction illustrated which might materially change the appearance thereof, while still involving the ideas and appropriating the utilities suggested by the invention here disclosed. 8

Having described my invention, what I claim as new, and desire to secure by Letters Patent, is—

1. In combination with a radiator, rods passing between the sections thereof, each of said rods having an adjusting-nut at one end and a head at the other end, a shelf pivotally mounted with respect to said rods and a notched arm pivotally connected to said shelf and adapted to engage a detent-plate connected to 85 said radiator.

2. In combination with a radiator, rods passing between the sections thereof, each of said rods having an adjusting-nut at one end and a head at the other end, a shelf pivotally mounted with respect to said rods and a notched arm pivotally connected to said shelf and adapted to engage a detent-plate adjustably connected to said radiator below that part upon 95 which said shelf is mounted. 100

3. In combination, means adapted to be adjustably secured to a radiator, a shelf pivotally mounted thereon, a member adapted to be secured to the radiator at a lower point, and 5 a notched arm pivotally secured to said shelf and adapted to rest with its notched surface in engagement with said member.
4. In combination, means adapted to be adjustably secured to a radiator, a shelf pivotally mounted thereon, a member adapted to be secured to the radiator at a lower point, a notched arm pivotally secured to said shelf and extending downwardly into engagement with said member, and a handle upon said shelf.
- 15 5. In combination, two rods adapted to extend between the sections of a radiator and having adjustable means thereon adapted to engage said sections and maintain said rods

in fixed relation thereto, each of said rods being provided with a portion extending substantially at right angles with the body thereof, a shelf pivotally mounted upon said last-mentioned portions of said rods, a detent-plate, a rod connected with said detent-plate 25 adapted to pass between sections of the radiator and be adjustably secured thereto, a notched bar pivotally mounted upon said shelf having a portion extending downwardly into engagement with said detent-plate, and a handle projecting upwardly from said shelf.

In testimony whereof I affix my signature in the presence of two witnesses.

EUGENE TERRY.
